UNITED STATES PATENT OFFICE.

JOHN S. BRENNAN, OF MILWAUKEE, WISCONSIN.

BURNER-DRUM-LIFTING MEANS.

Application filed May 18, 1920. Serial No. 382,387.

To all whom it may concern:

Be it known that I, JOHN S. BRENNAN, a citizen of the United States, and resident of Milwaukee in the county of Milwaukee and State of Wisconsin, have invented certain new and useful Improvements in Burner-Drum-Lifting Means; and I do hereby declare that the following is a full, clear, and exact description thereof.

10 My invention pertains to new and useful improvements in the burners for oil and similar stoves such as that illustrated in my Patent No. 1,327,857, issued Jan. 13, 1920.

15 The primary object of the present invention is to simplify and improve the construction shown in this patent to render its operation more efficient and the cost of manufacture less expensive.

20 Specifically the objects of this invention are to provide an improved supporting bracket for mounting the burner head and burner drum lifting means; to provide an adjustable, extensible and contractible connection between the burner head and its 25 lifting means; and to provide a simple burner drum elevating mechanism.

With these general objects in view the invention resides in the novel features of construction, combination and arrangement of 30 parts which will be hereinafter more particularly described and claimed and shown in the accompanying drawing in which:

Figure 1 represents a view partly in side elevation and partly in section of a burner 35 embodying my invention.

Figure 2 is a rear elevational view of the lower portion of the burner unit.

In the preferred embodiment of the invention as shown in the said drawing, reference character 1 denotes a main supply pipe 40 which, as is common in stoves of this character, extends horizontally from one end to the other thereof, and is fed from a suitable constant level supply reservoir, and has a vertical upstanding supply pipe branch 2 for each burner head 3. In the present instance each burner head includes an annular trough 4 having an inlet into its bottom through which fuel is supplied from a supply stem 5, the latter being telescopically 45 slidably in one of said supply pipe branches 2. Associated with this conventional structure is a burner drum 6, which drum can be seated upon the burner head or spaced 50 therefrom as desired.

The burner head 3 is raised and lowered

by suitable means to be described which is carried by an improved bracket 7, the same being formed from a plate having an intermediate attaching portion 8 engaged with the supply pipe branch 2 and extended vertically, a horizontal brace arm 9 extending forwardly of the stove, and a rearwardly projecting horizontal guide arm 10. From Figure 1 it will be seen that the arms 9 and 10 extend in opposite directions from the upper and lower ends of the attaching portion 8 and that said arm 9 adjacent this connection with the intermediate attaching portion is provided with a hole receiving the supply pipe branch 2. The bracket is secured upon said supply pipe branch 2 by means of an encircling clip 11, which clip and the vertical attaching portion 8 are clamped about said branch 2 by bolts and nuts 12.

The forward or free end of the arm 9 depends downwardly as at 13, and is secured to a vertical brace plate 14 forming a portion of the stove frame, and has an operating shaft 15 journaled therein, said shaft being also journaled in the intermediate attaching portion 8. The outer end of the shaft 15 has a handle 16 secured thereto and also an indicating pointer 17 which is adapted to co-operate with a dial formed on the brace plate 14. The inner end of the shaft carries a crank 18 connected with the burner head 3 by the two parts 19 and 20 of an extensible and contractible link.

The parts 19 and 20 form a pair of link arms, one being pivoted as at 21 to the inner wall of the burner head, whereas the other link arm 20 is pivoted to the crank 18. One of the link arms is slotted as at 22 and the other has clamp bolts 23 extending through said slots to secure the two parts together. By such an arrangement the burner head may be readily adjusted with respect to the crank 18, and thus a considerable range of movement of said head is possible by the rotation of the shaft 15.

The burner drum 6 is adapted to be moved, that is to say raised or lowered, independently of the burner head 3, and for this purpose a lifting rod 24 is extended through the burner head and slidably journaled in a plate 25 carried thereby. The upper end of this rod 24 has a head 26 engaging a portion of the drum 6 which is seated thereon as indicated in Figure 1, the lower end, on the other hand, being slidably

journalled in said guide arm 10 of the bracket 7.

The last mentioned portion of the lifting rod 24 has a laterally extending handle member 27, the free end of which forms a handle proper 28 and the intermediate part has an inverted U-shaped yoke 29 provided therein. It will be seen from Figure 2 that the handle member 27 is offset as at 30 with respect to the vertical plane of the main portion of the rod 24.

When the burner structure is in use and the burner drum 6 is in normal position, the yoke 29 straddles the main supply pipe 1 and is seated thereon, as a result of which said supply pipe provides a support for said drum. On the other hand when the burner drum 6 is to be elevated for any purpose, for instance to light the burner head, the operator lifts upwardly on the handle 28 and after the yoke 29 is disengaged from the supply pipe 1, the rod 24 is rotated slightly to disaline said yoke and said main supply pipe 1 as shown in dot and dash lines in Fig-

ure 1. Thus when the handle 28 is released, 25 the same is adapted to seat on the main supply pipe 1 and to support the burner drum in its elevated position.

I claim:

In a burner structure, a burner head, a supply pipe having a substantially horizontal and a vertical portion on which the head is supported, a burner drum normally seated on the burner head, a substantially vertical lifting rod connected with the drum, 35 the lower end of the rod having an inverted U-shaped extension adapted to seat on said horizontal portion when the drum is in its lowered position, and a handle on the outer end of said extension engageable with said 40 said horizontal portion to support the drum when the latter is in its elevated position.

In testimony that I claim the foregoing I have hereunto set my hand at Milwaukee in 45 the county of Milwaukee and State of Wisconsin.

JOHN S. BRENNAN.
